WATER-CONTAINING PLAY TOY

Alex F. Miller and Rodger W. Hardin, Long Beach, Calif.

Application November 24, 1958, Serial No. 53,512

Term of patent 14 years

(Cl. D34—15)

Figure 1 is a perspective view of a water-containing play toy showing our new design with the cover in position; and

Figure 2 is a perspective view of a water-containing play toy showing our new design with the cover removed.

We claim:

The ornamental design for a water-containing play toy, substantially as shown.
